(57) **CLAIM**

We claim the ornamental design for the kick stand, as shown and described.

DESCRIPTION

FIG. 1 is a right-side elevation view of a kick stand showing the new design.

FIG. 2 is a top plan view of a kick stand showing the new design.

FIG. 3 is a rear elevation view of the kick stand showing the new design.

FIG. 4 is a left-side elevation view of a kick stand showing the new design.

FIG. 5 is front elevation view of the kick stand showing the new design.

FIG. 6 is a bottom view of the kick stand showing the new design.

FIG. 7 is a right-side elevation view of the kick stand in an open and engaged position to support a motorcycle; and, FIG. 8 is a front elevation view of the simulative barrels shown in FIG. 7, shown separately for clarity.

The phantom lines in the figures are intended only to aid in the understanding of the claimed design, are for illustration purposes only showing an article upon which the claimed design may be associated or applied, and form no part of the claimed design.
